SPEED WRENCH

Oswald M. Gross, Detroit, Mich.

Application January 15, 1935, Serial No. 1,969

3 Claims. (Cl. 81—134)

The invention forming the subject matter of this application relates generally to wrenches of the type in which the jaws are self-adjusting to fit nuts and bolt heads of various sizes.

5 The main object of the invention is to provide a wrench of the character referred to, in which the jaws contract automatically to fit nuts and similar objects of various sizes, to be turned in one direction or another; and, in which the jaws remain in contact with the object, at all time, during the operation of tightening or releasing the same.

10 A further object of the invention is to provide a wrench of the type referred to, which can be very cheaply manufactured in large quantities; and in which the parts are few in number, of maximum strength, and designed so as to facilitate the taking apart or assembly of the parts for replacement or repair.

15 Other objects of the invention will appear as the following description of a preferred and practical embodiment thereof proceeds.

In the drawings:

Figure 1 is a part section taken lengthwise on line 1—1 of Figure 2 in open position through one form of wrench embodying the present invention;

Figure 2 is a right hand end elevation of the wrench illustrated in Figure 1;

Figure 3 is a side elevation of the wrench illustrated in Figures 1 and 2, showing the jaws thereof in closed position;

Figure 4 is a left hand end elevation of the wrench shown in Figure 1;

Figure 5 is a fragmentary detail in perspective of part of the device shown in Figure 1;

Figure 6 is a fragmentary central section through the lower part of a modified form of the gripping mechanism illustrated in Figure 1;

Figure 7 is a fragmentary exploded perspective view of parts of the invention shown in Figure 6;

Figure 8 is a side elevation of a slightly modified form of the wrench illustrated in Figures 1 to 4;

Figure 9 is a fragmentary control section of the lower operating mechanism of another modified form of the invention;

Figure 10 is a right hand end elevation of the parts shown in Figure 9;

Figure 11 is a perspective view of a lever forming part of said mechanism;

Figure 12 is a fragmentary central section of the operation mechanism in still another modification;

Figure 13 is a broken perspective of the jaw bar of the modification shown in Figure 12; and

Figure 14 is a right hand end elevation of the device shown in Figure 12, parts being broken away to illustrate certain details of construction.

Referring to Figures 1 to 5, inclusive, of the drawings, the reference numeral 1 designates a casing or housing which forms the body of the wrench. The casing 1 is provided near its lower end with a curved offset 2 designed to prevent the hand of the user from sliding off the wrench when the latter becomes greasy. The upper part of one edge of the casing 1 is provided with the usual grip corrugations 3; and is outwardly curved to form the lower jaw 4. The upper jaw 5 is formed at the upper end of a jaw bar 6 slidably mounted in the casing 1; and the outer end of the jaws 4 and 5 are shaped to provide inwardly inclined surfaces 7 and 8, respectively, adapted by pressing the inclined surfaces 7 and 8 against a nut or bolt head to effect separation of the aforesaid jaws.

The lower part of the casing 1 is slotted rearwardly to receive a lever 9 pivoted between its ends on a stud 10 suitably secured to the opposite sides of said casing 1. The lower arm 11 of the lever 9 is curved to conform to the general shape of the casing 1, and forms a closure for the lower end of said casing. The inner end of the arm 11 is provided with a slot 12 to receive the lower end 13 of a tension spring S suitably secured to a pin 14 extending across the slot 12.

As will be apparent from Figure 1 of the drawings, the upper part of the jaw bar 6 slides snugly in the casing 1. This jaw bar 6 is provided at its inner edge with a comparatively long recess 15 adapted to receive the coiled part 16 of the tension spring S. The upper end of this coiled part 16 is suitably secured in bore 17 to the jaw bar 6 near the upper end of the recess 15. The lower end 18 of the jaw bar 6 is shaped to slide against the inner face of the housing 1; and is provided with a bore 19 through which the straight part 13 of the tension spring S passes freely.

The rear edge of the jaw bar 6 is provided with a recess 20 to form a clearance for the upper end 21 of the lever 9. This recess 20 at its lower end is shaped to form a serrated surface 22 inclined outwardly toward the lower end of the jaw bar 6. This serrated surface is adapted to co-operate with a similarly inclined serrated surface 23 formed on an inwardly projecting part 24 of the lever 9. The lever 9 adjacent the pivot 10 is provided with a bore 25 in which is seated the coils 26 of a spring designated generally by the reference numeral 27. One end of the spring 27 ex-

tends upwardly from the coiled part 26 to form a substantially straight arm 28 contacting at its upper end with a shoulder 29 formed by a slot 30 extending transversely across the lower part 5 of the jaw bar 6. At the other end of the coil spring 27, an arm 31 extends upwardly along the opposite side of the lever 9; and an inwardly turned lug 32 formed at the end of the arm 31 seats in the corner of a recess 33 formed in the 10 upper arm 34 of the lever 9.

A bore extends transversely through the jaw bar 6 and receives a pin 36 suitably secured to a cap 37 which normally closes a slot 38 formed in one side of the casing 1. The cap 37 is adapted 15 to be engaged by the thumb of the user to effect an initial spreading apart of the jaws 4 and 5; and the upper end of the slot 38 acts as a stop to limit the separation of these jaws.

It is believed that the operation of this form 20 of the invention will be apparent to persons skilled in the art from inspection of Figures 1 to 5 of the drawings.

The modification shown in Figures 6 and 7 of the drawings is intended for use for large size 25 wrenches. In this modification the jaws (not shown) are substantially the same as those shown in Figure 1. The tension spring is omitted and a different form of grip mechanism is used at the lower end of the wrench.

30 In the casing 42, the jaw bar 43 is mounted to slide, and is held normally in yielding jaw-closing position by means of the spring 44 and operating levers 45 and 46 connected therewith. One of these levers 45 is pivoted to the casing 42 to swing about the pivot 42'; and is shaped to form a closure for the lower end of casing 42. The upper end of the lever 45 is provided with a shoulder 47 adapted to engage a shoulder 48 on the casing 42 to limit the outward movement of the lever 45.

40 The lever 46 is provided at its upper end with an inwardly projecting tooth 49 adapted to engage the serrations 50 formed on the back edge of the lower part of the jaw bar 43; and a stop 51 engages the tooth 49 when the jaws are fully separated. The lower part of lever 46 is shaped to form a serrated V-shaped lug 52 slideable in a correspondingly shaped and serrated channel 53 formed in the lower part of the jaw bar 43.

50 A notch 54 is formed in the lower end of the jaw bar 43 to receive one end of the spring 44, the central coiled part of which is seated in a bore 56 extending transversely through the lower end of lever 46. The other end of the spring 44 is bent up around the rear edge of the lever 46, and is hooked through an aperture 57 formed in said lever.

60 The operation of this form of the invention is substantially the same as that of the wrench shown in Figures 1 to 5.

In the form of the invention illustrated in Figure 8, the curved offset 2 is omitted; and the curved offset 39 of Figures 1 and 3 of the drawings has also been omitted, the gear edge of the 65 housing 1 extending downwardly without offset to a part 40 adjacent the pivot 10. The various edges of the housing and the jaw bar may be bevelled as indicated by the reference numeral 41 to remove surplus metals for the purpose of reducing the size of the wrench and also to adapt the 70 wrench for work in confined places.

In Figure 8 the jaws of the wrench are shaped to adapt them for use on hexagon nuts. It is intended, however, that the jaws in all the other 75 wrenches disclosed herein may be similarly

shaped if desired. In all other respects this form of the invention is similar to that shown in Figures 1 to 5.

In the form illustrated in Figures 9 to 11, the lower end of the casing 53 is slotted to receive the locking lever 54 shaped to make a comfortable fit in the hand of an operator. The upper back part 55 of the rear edge of the casing is preferably straight and terminates at its lower end in two outwardly directed lugs 56 and 57, 10 forming a slot 58, in which the upper reduced part 59 of lever 54 is received snugly.

The reduced part 59 is provided with an aperture 60 to receive a pivot pin 61 suitably secured to the lugs 56 and 57. Said part 59 has a stop 15 lug 62 extending upwardly therefrom and adapted to contact with the lower end 63 of the upper part 55 to limit the outward swing of the lever 54 about pivot 61.

The front edge of the jaw bar 64 is provided 20 with a recess 65 similar to the recess 15 in Figure 1; and a tension spring 66 is located on said recess with its upper end suitably fixed to the upper end 67 of the recess. The lower part 68 of spring 66 extends as a straight wire through a 25 bore 69 of lower end of jaw bar 64 extending through the lug 70 at the lower end of recess 65 and at its lower end is suitably secured to the lower end of one arm 71 of a lever 72 which is pivoted between its ends by means of a fulcrum pin 30 73 extending across the slot in the lower end of casing 53.

The arm 74 of lever 72 is recessed at its inner edge to permit the jaw bar 64 to slide freely in casing 53 toward and from the lower end thereof; and the said arm 74 has a part 76 at its upper end serrated and V-shaped in cross section to co-operate with a serrated and V-shaped channel 77 formed along the rear edge of jaw bar 64 near the lower end thereof. The construction of 40 the parts 76 and 77 is similar to that shown in Figure 7.

The back edge of the arm 74 of lever 72 at its upper end is shaped to form a contact bearing for the projecting lug 78, on the lever 54 near its upper end. The adjacent edges of levers 72 and 54 are shaped to form a clearance 79 sufficiently large to permit the spring 68 to hold the arm 74 with its upper serrated end 76 normally out of locking contact with the lower serrated end of jaw 50 bar 64.

In the form of the invention shown in Figures 12, 13 and 14, the front edge of casing 80 has a boss 81 suitably secured thereto as by welding or otherwise. The boss 81 is bored to receive a pin 55 or rivet 82 extending through the lugs 83, and 84 projecting laterally from the upper end of a locking member 85, which is substantially U-shaped in cross section.

The lower part of casing 80 adjacent the member 85 is also U-shaped in cross section, and has its sides 86 and 87 straddled by the sides 88 and 89 of the member 85. The jaw bar 90 slides in the U-shaped channel formed by the sides 86 and 87; 65 and has its rear edge recessed and provided with serrations 91 adapted to interlock with serrations 92 formed on the inner edge of a block 93 secured in the channel formed by the sides 88 and 89 near the upper end thereof. 70

The lower end of the jaw bar 90 has a transverse slot 94 formed therein and shaped to provide a curved contact surface 95 for one end of the arm 96 of a spring 98, which is coiled at its center and is suitably secured to the member 85 75

by means of the pin 97 which is secured to sides of member 85.

It is believed the operation of the several forms of this invention will be obvious to persons skilled in the art by inspection of the drawings forming part of this specification.

What I claim is:

1. A wrench comprising a handle formed as a casing having a jaw at one end thereof, a bar 10 slideable in said casing and having a jaw at one of its ends cooperating with the jaw in said casing, a lever pivoted intermediate its ends near the lower end of said casing, yielding means connected to said bar and to one arm of said lever for holding 15 the casing and bar with their cooperating jaws normally in yielding contact with each other, said lever and the lower end of said bar being provided with serrations, yielding means for holding said lever with its said serrations normally out of contact with the serrations on said bar, the other arm 20 of said lever being operable by gripping pressure exerted in the direction of the bar to lock said casing and bar with their jaws in any desired position of relative adjustment.
2. A wrench comprising a handle formed as a casing having a jaw at one end thereof, a bar having a jaw at one end and slidably mounted in 25 said casing, said bar having serrations along one edge, a lever fulcrumed between its ends to the

lower part of said casing and having serrations on one of its arms adapted to interlock with the serrations on said bar, and yielding means connecting said jaw to the other arm of said lever for normally holding said lever with its serrations out of contact with the serrations on said bar, said serrated arm being movable by pressure to cause the serrations to interlock at any desired relative adjustment of said casing and bar.

3. A wrench comprising a handle formed as a 10 casing having a jaw at one end thereof, a bar having a jaw at one end and slidably mounted in said casing, said bar having serrations along one edge, a lever fulcrumed between its ends to the lower part of said casing and having serrations on 15 one of its arms adapted to interlock with the serrations on said bar, said bar having a recess formed in its opposite edge, a tension spring located in said recess and having one end secured to the bar at the end of the recess nearest the 20 jaws of the wrench, the other end of the spring passing freely through an aperture in the bottom wall on the recess and being fixed to the other arm of said lever to hold the lever normally in unlocked relation to said bar, said lever being 25 movable against the tension of said spring to lock the bar in any desired position in said casing.

OSWALD M. GROSS.
